DESIGN FOR A BAG FRAME

Charles McLaughlin, Garden City, N. Y., assignor to Tilton & Cook Co., Leominster, Mass., a corporation of Massachusetts

Application April 15, 1939, Serial No. 84,324

Term of patent 3½ years

To all whom it may concern:

Be it known that I, Charles McLaughlin, a citizen of the United States, residing at Garden City, in the county of Nassau, State of New York, have invented a new, original, and ornamental Design for a Bag Frame, of which the following is a specification, reference being had to the accompanying drawing, forming part thereof.

In the drawing, Fig. 1 is a front elevational view of a bag frame showing my new design; Fig. 2 is a top plan view of the same; and Fig. 3 is an end elevational view of the same.

I claim:

The ornamental design for a bag frame, substantially as shown.

CHARLES McLAUGHLIN.
